UNITED STATES PATENT OFFICE

2,563,181

CONVEYER

Eric O. Melmer, Detroit, Mich., assignor to Anchor Steel & Conveyor Company, Detroit, Mich., a corporation of Michigan

Application April 12, 1948, Serial No. 20,482

8 Claims. (Cl. 198—131)

1

This invention relates broadly to new and useful improvements in conveyor apparatus.

In the manufacture of certain types of axle housings, preformed, generally tubular sections are heat-treated in a slot furnace. These sections or workpieces are moved at a more or less uniform rate through the furnace, and they should be rotated continuously when in the furnace so that all portions thereof within the furnace are uniformly affected by the heat.

The present invention is concerned primarily with means for moving a continuous procession of axle-housing sections or similar workpieces through a slot furnace, and the apparatus includes means for automatically rotating the workpieces continuously and at a uniform rate during their travel through the furnace.

Heretofore, some difficulty has been encountered in disengaging the heated workpieces from the supporting mandrels as they emerge from the furnace. The present apparatus also includes a novel means for performing the above operation mechanically and automatically.

From the foregoing it will be readily apparent that an important object of the present invention is to provide a conveyor which will move a plurality of axle-housing sections or the like progressively through a slot furnace and then automatically disengage the sections from the supporting mandrels as they emerge from the furnace.

Another object of the invention is to provide a conveyor of the above-mentioned character which automatically rotates the workpieces continuously and at a uniform rate during their travel through the furnace to assure a uniform application of heat thereto.

Still another object of the invention is to provide a conveyor apparatus that automatically disengages the heated workpieces from the supporting mandrels immediately after the latter leave the furnace, whereby to eliminate manual handling of the same.

Yet another object of the invention is to provide a conveyor apparatus of the above-mentioned character that is relatively simple in construction but at the same time is highly efficient in operation.

Other objects and advantages of the invention will be apparent during the course of the following description.

In the drawings forming a part of this specification and wherein like numerals are employed to designate like parts throughout the same:

Fig. 1 is a side elevational view of a conveyor apparatus embodying the invention;

2

Fig. 2 is an enlarged, fragmentary, transverse, vertical sectional view taken on the line 2—2 of Fig. 1;

Fig. 3 is a vertical, longitudinal sectional view taken on the line 3—3 of Fig. 2;

Fig. 4 is a fragmentary, vertical, longitudinal sectional view taken on the line 4—4 of Fig. 2;

Fig. 5 is a vertical, transverse sectional view taken on the line 5—5 of Fig. 1;

10 Fig. 6 is a fragmentary plan view looking in the direction of the arrows 6—6 in Fig. 1;

Fig. 7 is a fragmentary, vertical, longitudinal sectional view taken on the line 7—7 of Fig. 6; and

15 Fig. 8 is a fragmentary plan view looking in the direction of the arrows 8—8 in Fig. 7.

In the drawing, wherein for the purpose of illustration is shown a preferred embodiment of the invention, the numerals 10 and 12 designate 20 a pair of vertically disposed, endless conveyor chains. The conveyor chains 10 and 12 are arranged side by side in laterally spaced relation, as perhaps best shown in Fig. 2.

Any suitable or conventional construction may 25 be employed for the conveyor chains 10 and 12. For the purpose of illustration, however, the chains are here shown as comprising relatively short, spaced pairs of links 14 connected end to end by pivots 16. Rollers 18 are carried by the pivots 16 between the various pairs of links.

30 Each of the conveyor chains 10 and 12 is trained over a group of sprockets 20, and the latter are carried by a suitable supporting framework designated generally by the numeral 22. In the form of the invention here shown by way 35 of illustration, corresponding sprockets 20 in each group are rotatably driven and the other sprockets in the groups are merely idler sprockets. It will be readily understood, however, that, if desired, two or more driving sprockets may be 40 employed and the driving forces of these sprockets co-ordinated by conventional means. The driving sprockets are here shown at the rearward end of each conveyor chain. These two sprockets are fixed on a common shaft for mutual rotation and this shaft also causes a driving sprocket 20a which is rotatably driven by a motor 24 through a gear reduction unit 26 and intermediate drive sprockets 28 and 30. As shown 45 in Fig. 1, the motor 24 and gear-reduction unit 26 are both mounted on the frame 22 and the driving pulley of the motor is connected to the driven pulley of the gear-reduction unit by an endless belt 32. The two sprockets 28 and 30 are fixed on opposite ends of a jack shaft 34 and 50 the latter is mounted for rotation in suitable

55

journals on the supporting frame work 22. The power take-off sprocket of the gear-reduction unit 26 is connected to the sprocket 28 by an endless chain 36, and the sprocket 30 is connected to the driving pulley 20a by an endless chain 38.

As clearly shown in the drawing and particularly in Fig. 1, the sprockets 20 are arranged so that the two chains 10 and 12 assume substantially the shape of a parallelogram when viewed in side elevation. Both chains 10 and 12 are the same length, and the two sets or groups of sprockets 20 are identically located and of the same size. Thus, since the driving sprocket 20a and the two conveyor sprockets are mounted for mutual rotation on a single shaft, the two chains 10 and 12 are operated simultaneously at the same speed. As shown in Figs. 2 and 5, the supporting framework 22 includes members 22a of angle iron or the like, which members extend under and support the rear portions of the upper and lower runs of the conveyor chains 10 and 12.

The conveyor is mounted in front of a slot furnace designated generally by the numeral 40 with the upper runs of the chains 10 and 12 arranged parallel to the front of the furnace and slightly below the slot 42 (Fig. 5). The furnace 40 is conventional and need not be described in detail. Workpieces 44 carried by the conveyor extend into the slot 42, as shown in Fig. 5; and, as the conveyor moves the work longitudinally along the slot, they are heated to the desired temperature by suitable heating means within the furnace. The conveyor chains may be of any suitable length, but they should be at least long enough so that the upper runs thereof extend the full length of the furnace 40. In Fig. 1 both the furnace 40 and the conveyor are shortened by the omission of intermediate portions thereof. In actual practice, both the furnace 40 and the conveyor are quite long, and the exact length may vary considerably according to the exigencies of the particular situation. Also a portion of the supporting framework which carries the conveyor chains preferably is adjustable relative to the furnace 40 to permit proper positioning of the workpieces 44 in the slot 42 and so that the apparatus can be adapted to various types and sizes of workpieces.

The means for mounting the workpieces 44 on the conveyor chains 10 and 12 is now described in detail. In this connection, it will be observed that the inner links 14 of each chain 10 and 12 carry standards 46 and that corresponding standards on the two chains are disposed directly opposite each other. The standards 46 here shown comprise vertically elongated metal plates or strips which are welded or otherwise fastened to the links 14. As best shown in Fig. 2, the standards 46 extend substantially above the chains 10 and 12, and each pair of opposed standards carries a transverse tubular housing 48. Preferably, the tubular housings 48 extend through openings in the supporting standards 46 and are welded to the standards as at 50 (Fig. 2) to assure an essentially strong, rigid structure. Preferably, gussets 52 also are welded to the standards 46 and housing 48, as shown in Fig. 2, to increase the rigidity of the structure and to prevent the conveyor from being pulled laterally when the workpieces 44 are pulled from the supporting mandrels. From the above it will be readily apparent that each pair of inner links 14 carries a tubular housing 48 and that the

5 housings extend continuously around the conveyor chains 10 and 12.

Spindles 54 are mounted in the housings 48, and the spindles are supported for rotation by roller bearings 56 located adjacent the ends of the housings. Suitable "alemite" fittings 58 carried by the housings 48 permit lubrication of bearings 56. Sleeves 60 are inserted in the housings 48 behind the rearmost bearings 56, and the sleeves are retained in the housings by washers 62 on the projecting ends of spindles 54. The washers 62 in turn are held in place and axial movement of spindles to the left, as viewed in Fig. 1, is limited by collars 64 which are fastened on the projecting terminal portions of the spindles by bolts 66 and nuts 68. Dirt and other foreign matter are prevented from gaining access to the forward bearings 56 by washers 70 which fit over the spindles 54 and against the forward ends of the housing 48.

Also, it will be observed that mandrels 72 are fastened on the forwardly projecting ends of the spindles 54 by bolts 73 and nuts 75, which mandrels are adapted to carry the workpieces 44. As suggested, the present invention is primarily adapted and pre-eminently suited for heat-treating axle housing sections, and to this end the mandrels 72 are formed with relatively elongated, longitudinally tapered, generally cylindrical terminal nose portions 74 which are adapted to extend into and to snugly fit the housing sections. Also, it will be observed that the mandrels 72 extend laterally of the supporting framework 22 and substantially to the front face of the furnace 40 so that the workpieces 44 extend into the furnace through the slot 42 (Fig. 5).

In practice the conveyor travels continuously so that the workpieces 44 are carried in endless procession through the furnace. The workpieces 44 are pushed onto the mandrels 72 as the latter approach the furnace 40 either manually or by suitable mechanical means, and they are removed from the mandrel as they emerge from the furnace.

In order to assure a uniform heat treatment, it is desirable that the workpieces 44 be rotated continuously as they pass through the furnace 40. To this end I mount a track 78 on the supporting framework 22 between the endless chain 10 and the furnace 40 where it will be engaged by the mandrels 72 (Fig. 2). The track 78 extends at least the full length of the furnace 40. As the workpieces 44 enter the furnace 40, the mandrels 72 which carry them move onto the track 78; and as the workpieces 44 move through the furnace, frictional engagement between the mandrels 72 and the track 78 effects rotation of the mandrels and consequently of the workpieces carried thereby. This friction drive is an important feature of the invention since it provides a mechanically simple yet highly efficient rotary drive for the workpieces 44. Preferably, the portions of the mandrels 72 which engage the track 78 are formed with annular grooves 80. Thus after the mandrels 72 ride up on to the track 78, the side walls of the grooves 80 limit lateral movement of the mandrels and assure uniform positioning of the workpieces 44 in the furnace 40. After the workpieces emerge from the furnace the mandrels 72 roll off the end of the track 78, and rotation of the mandrels ceases at this point.

I also provide a second track 82 behind conveyor chain 12, which track is engaged by rollers 84 on the rearward ends of the housings 48. The

rollers 84 are supported for rotation on the housings 48 by sleeve bearings 86 and are confined between the washers 62 and collars 88 which are welded or otherwise fastened to the housings immediately in front of the rollers. In this connection it will be observed that the rollers 84 rotate freely or idly on the housings 48. They form no part of the rotary drive for the mandrels 72, but merely support the rearward ends of the housing 48 and thus position the mandrels for proper insertion of the workpieces 44 into the furnace 40.

Also, I provide a rail 90 immediately above the rear rollers 84. This rail 90 is spaced slightly above the rollers 84 when the latter engage the rail 82, but are engaged by the rollers 84 to limit rocking movement of the housings 48 if there is any tendency for the workpieces 44 to tip the housings on the rail 78.

The means for removing the heated workpieces 44 from the mandrels 72 also is a feature of this invention. In this connection, it will be observed that the nose portions 74 of mandrels 72 are formed with longitudinal slots 92 and that double-headed pins 94 are mounted to move freely back and forth in the slots. As perhaps best shown in Fig. 3, the enlarged ends of the pins 94 prevent the latter from dropping out of the slots 92 and at the same time permit the pins to move freely longitudinally in the slots.

When the workpieces 44 are pushed onto the mandrels 72, they engage the projecting ends of pins 94 and push the latter rearwardly in the slots 92. Thus the pins 94 normally occupy retracted positions in the slots 92; and during the heat-treating operation, they are held in retracted positions by the workpieces 44.

As the workpieces 44 emerge from the furnace 40, the mandrels 72 roll off the ends of the tracks 78 and 82 and the rollers 18 of conveyor chains 10 and 12 drop downwardly a short distance onto the angles 22a, which then support the conveyor and its appurtenances until the mandrels are pushed up and supported by transfer strips 102. The transfer strips direct the mandrels between a pair of vertically spaced cam strips 96. As the mandrels pass between the cam strips 96 the projecting ends of the pins 94 engage the leading cam edges of the strips. These edges are curved outwardly away from the adjacent conveyor chain 10 and advance the pins in the slots 92 as the mandrels are pulled between the cam strips 96 by the conveyor.

As suggested, two identical cam plates 96 are provided, and the cam plates 96 are fastened to the supporting framework 22, as best shown in Figs. 6, 7, and 8. Both ends of the ejector pins 94 engage the cam plates 96 simultaneously and pressure is applied uniformly against both ends of the pins to advance the same in slots 92. As the pins advance they push against the adjacent ends of the workpieces 44 and eject the latter from the mandrels 72. In practice, the cam plates 96 push the ejector pins 94 outwardly substantially to the ends of slots 92 and then disengage the pins. Thus the ejector pins 94 pass over the ends of cam plates 96 after they have been substantially fully advanced in slots 92. Manifestly, after the mandrels pass beyond the cam plates 96, they merely continue on around the conveyor and thereafter they serve no useful purpose until they again approach the furnace 40, at which time workpieces are again inserted thereon and the cycle of operation is repeated. Any suitable means such as an endless conveyor

(not shown) may be provided to catch the workpieces 44 as they fall from the mandrels 72 and to carry the same away for further processing or other disposition.

From the foregoing it will be readily apparent that the ejector pins 94 must be disposed vertically at the time they pass between the cam plates 96 in order to effect engagement between the projecting ends of the pins and the leading edges of the cam plates. In order to assure proper angular or rotative position of the mandrels 72, I provide the nose portions 74 with flat surfaces 98, which surfaces are disposed on opposite sides of the mandrels and extend transversely to the slots 92. The surfaces of the mandrels 72 intermediate the flat surfaces 98 are rounded as at 100. Also, it will be observed that the cam plates 96 are spaced longitudinally from the track 78 (Fig. 8), and that a transfer strip 102 is mounted forwardly of and in alignment with the lower cam plate 96. The forward portion 104 of the transfer strip 102 is lower than the rearward or distal portion 106 thereof, and the two portions 104 and 106 are joined by an integral gradually inclined portion 108. The transfer strip 102 extends longitudinally beyond and is disposed laterally of the track 78. Preferably the forward terminal portion 104 of the transfer strip 102 overlaps the rearward terminal portion of the track.

In practice the mandrels 72 may be in any angular position until they are picked up by the inclined portion 108 of the transfer strip 102. As they slide along the inclined surface 108, the mandrels 72 are rotated until one or the other of the flat surfaces 98 engages the strip 102. Thus, all of the mandrels are identically positioned as they move onto the rearward portion 106 of the strip 102. Also, the weight of the mandrels is transferred from the angle supports 22a to the strip 102 substantially at the time the mandrels are picked up by the portion 108 so there is no tendency for the mandrels to rotate on the transfer strip at the time the mandrels reach the terminal portions 106 of the strip. The flat surfaces 98 merely slide along the transfer strip 102 and onto the lower cam plate 96. Manifestly, the ejector pins 94 will be positioned vertically for proper engagement by the cam plate 96 regardless of which surface 98 is in engagement with the transfer strip.

From the foregoing it will be readily apparent that I have achieved the objects of my invention. I have provided a conveyor for moving workpieces in endless succession through a slot furnace at a uniform rate of travel. Also, I have provided means for automatically continuously rotating the workpieces during their entire travel through the furnace to assure a uniform application of heat thereto. After the workpieces emerge from the furnace, they are removed automatically from the conveyor for further treatment. The apparatus is adapted to a furnace of substantially any size and will perform its intended function efficiently under a variety of conditions.

It is to be understood that the form of the invention herewith shown and described is to be taken as a preferred example of the same and that various changes in the size, shape and arrangement of parts may be resorted to without departing from the spirit of the invention or the scope of the appended claims.

Having thus described the invention, I claim:

1. In apparatus of the described, a mandrel

having a terminal portion adapted to enter and snugly fit a hollow workpiece and provided with a longitudinal slot; an ejector member mounted for movement back and forth between retracted and advanced position in said slot and having radially projecting portions adapted to engage one end of said workpiece; means for moving said mandrel bodily along a predetermined path of travel; a friction drive for rotating said mandrel during at least a portion of its travel; cam means located to be engaged by the projecting portions of said ejector when the latter is in a retracted position in said slot and the mandrel is moved to a predetermined point in its travel, said cam means being operative to advance said ejector in said slot as the mandrel is moved beyond said predetermined point and to release said ejector when the latter is substantially fully advanced in said slot.

2. The combination as set forth in claim 1 wherein the means for moving said mandrel comprises an endless conveyor having an upper run portion and wherein said cam means is located adjacent one end of said upper run portion.

3. In apparatus of the character described, a tube support having a terminal portion adapted to enter and snugly fit a hollow workpiece and provided with a longitudinal slot; an ejector member mounted for movement back and forth in said slot and having radially projecting portions adapted to engage one end of said workpiece; means for moving said support bodily along a predetermined path of travel; means for rotating said tube support for at least a portion of its travel; cam means arranged to be engaged by the projecting portions of the ejector when the latter is in a retracted position in the slot and adapted to advance said ejector in the slot as the support moves beyond the point in its travel at which it engages the cam means so that said projecting portions eject the workpiece from the mandrel; and means for positioning said support for proper engagement of the ejector member with said cam means.

4. In apparatus of the character described, a mandrel having a terminal portion adapted to enter and snugly fit a hollow workpiece and provided with a longitudinal slot; an ejector member movable in said slot and provided with radially projecting terminal portions adapted to engage one end of said workpiece; an endless conveyor carrying said mandrel, said conveyor having an upper horizontal run portion; cam means located adjacent the end of said horizontal run portion arranged to be engaged by the projecting portions of said ejector when the latter is in a retracted position in said slot and adapted to advance said ejector in the slot upon continued movement of the mandrel by said conveyor so as to eject said workpiece from the mandrel; and means located immediately in front of said cam means for positioning and maintaining the mandrel in a predetermined rotated position permitting proper engagement of the ejector and said cam means.

5. In apparatus of the character described, a rotatable mandrel having a terminal portion adapted to enter and snugly fit a hollow workpiece and provided with a longitudinal slot; an ejector member mounted for movement back and forth in said slot and provided with radially projecting portions adapted to engage one end of said workpiece; an endless conveyor carrying said mandrel and having an upper horizontal run portion; means for rotatably driving said mandrel during a portion of its travel along said horizontal run portion; cam means behind said rotary drive means arranged to be engaged by the projecting portions of said ejector when the latter is in a retracted position in the slot and adapted to advance said ejector in the slot as the mandrel is carried by said conveyor beyond said point of engagement so as to eject said workpiece from the mandrel; and means disposed between said rotary drive means and said cam means for positioning said mandrel for proper engagement of the cam means by said ejector.

6. The combination as set forth in claim 5 wherein said cam means comprises upper and lower strips arranged to accommodate the terminal portion of said mandrel therebetween and located for edgewise engagement with the projecting portions of said ejector, the engaged edges of the strips curving laterally away from the conveyor so as to advance the ejector in longitudinal slot of the mandrel as the latter is moved longitudinally across the strips by the conveyor, and the distal ends of said strips terminating so as to release the ejector before the same is fully advanced in said slot.

7. The combination as set forth in claim 5 wherein said rotary drive means comprises an annular surface on said mandrel; and a track below said mandrel arranged for engagement with said annular surface.

8. The combination as set forth in claim 7 wherein said positioning means comprises flat surfaces on said mandrel, which surfaces extend transversely to and across the open ends of the slots; and a transfer strip between the track and said cam means, said strip adapted to support the mandrel during at least a portion of its travel between the track and the cam means and located to engage the flat surfaces of the mandrel whereby to prevent rotation of the latter and to deliver the same in a predetermined rotative position to the cam means.
